UNITED STATES PATENT OFFICE.

ALLISON M. MACFARLAND, OF BUFFALO, NEW YORK, ASSIGNOR TO LEO M. KOHN, OF BUFFALO, NEW YORK.

SHEET-FOLDING MACHINE.

1,313,712.

Specification of Letters Patent. Patented Aug. 19, 1919.

Application filed December 14, 1915. Serial No. 68,863.

To all whom it may concern:

Be it known that I, ALLISON M. MACFARLAND, a citizen of the United States, residing at Buffalo, in the county of Erie 5 and State of New York, have invented a new and useful Improvement in Sheet-Folding Machines, of which the following is a specification.

This invention relates to machines for 10 folding sheets of textile or analogous material.

The objects of the invention are to provide an efficient and reliable machine of this kind which is capable of operating on various 15 grades of textile material and to fold the same without wrinkling; also to provide a machine of this kind which is adapted to operate on sheets of different sizes; also to provide a machine of this kind which is provided with several folding mechanisms, 20 and with means for directing the sheets entering the machine to any one of said mechanisms; also to provide a machine of this kind which is adapted to fold sheets in 25 two directions if desired; also to provide a machine of this kind with a sheet receiving mechanism which is adjustable so that the folding machine can be placed into a 30 position to receive the sheets directly from a machine or apparatus from which the sheets are fed; also to provide a machine of this kind which is entirely automatic in its 35 action and which requires the minimum amount of attention; also to improve machines of this kind in the respects herein-after specified.

In the accompanying drawings:

Figure 1 is a longitudinal sectional elevation showing in outline a sheet folding apparatus embodying the invention.

Fig. 2 is a fragmentary top plan view thereof.

Fig. 3 is a longitudinal sectional elevation, 45 on an enlarged scale, of the primary folding mechanism of the apparatus.

Fig. 4 is a transverse sectional elevation thereof on line 4—4, Fig. 3 the edge folding belts being omitted.

Fig. 5 is a fragmentary longitudinal sectional elevation thereof showing the means for supporting the edges of the sheets.

Fig. 6 is a fragmentary longitudinal sectional elevation of the edge supporting means at the discharge end thereof.

Fig. 7 is a fragmentary transverse section 55 elevation thereof, on an enlarged scale, on line 7—7, Fig. 5.

Fig. 8 is a fragmentary sectional elevation on line 8—8, Fig. 3.

Fig. 9 is a diagrammatic plan view of the 60 folding and discharging devices of the primary folding mechanism.

Fig. 10 is a vertical sectional elevation of the secondary folding mechanism of the apparatus.

Fig. 11 is a top plan view thereof.

Fig. 12 is a fragmentary sectional elevation, on an enlarged scale, on line 12—12, Fig. 10.

Fig. 13 is a fragmentary sectional elevation, on an enlarged scale, on line 13—13, Fig. 11.

A represents the frame of the machine on which the parts of the folding mechanisms are suitably supported and which may 75 be of any suitable construction, that shown comprising a base a, upright members a', substantially horizontal members a² connecting the upright member a', and a table or plate a³ arranged on the top of the 80 frame.

The folding machine shown in the drawings comprises an upper folding mechanism or device B extending throughout the width of the machine and adapted to operate on 85 wide pieces or sheets, and folding mechanisms or devices C arranged below the wide folding device and adapted to operate upon narrow pieces or sheets. The folding machine is preferably arranged with its receiving end adjacent to the discharge end of an ironing machine or other device from which the sheets to be folded are delivered to the folding apparatus. D, Figs. 1 and 2, represents the discharge end of the ironing or 95 other machine (not shown), and E E' represent pivoted plates constituting the receiving platform of the folding machine. The plates are preferably pivoted at e and adapted to be swung into any one of three 100 positions indicated in Fig. 1, to deliver the sheets to a fixed receiving plate e' of the folding device B or to a fixed receiving plate e² of the folding devices C. If for any reason it is desired not to use the folding devices the pivoted receiving plates E E' can be swung into their upper position 105 in which the sheets will be discharged onto

the table a^2 . The pivoted ends of the receiving plates are preferably arranged above the level of the folding devices of the table a^2 so that the sheets can be easily 5 fed by gravity over the surface of the plates. In the use of the machine, if a sheet of substantially the width of the machine is to be folded, both plates are placed into operative position to the folding mechanism B. If 10 small sheets, such as towels or the like, are fed to the machine, the plates are placed into operative position to the plate e^2 of the group of folding mechanisms C. If some sheets of medium size are fed to the 15 machine, the larger plate E can be placed in position to feed these sheets to the mechanism B and the smaller plate E' can be placed into operative relation to one of the folding devices C, and the entire width of 20 the machine can then be utilized by feeding small sheets at the side of the larger ones. The positions of the plates E and E' may be regulated by means of arms e^3 and e^4 or any other suitable means. If desired, a 25 larger number of receiving plates may be provided. X represents a large sheet passing through the folding mechanism B.

If the discharge end D of the ironing or other machine is arranged below the level 30 of the folding devices or table a^2 , the sheets discharged therefrom can be fed into elevating means of any suitable construction. For this purpose two sets of rollers F F and F' F' are provided which are connected by 35 means of belts or tapes f f'. The adjacent pairs of rollers F and F' revolve in opposite directions and are so placed relatively to each other that two runs of the tapes f f' are in contact and move in the same direction. The contacting runs in the construction 40 shown move upwardly so that a sheet or article passing from the discharge end D of the ironing machine will pass between the contacting runs of the belts or tapes, and 45 will be drawn upwardly and discharged at the upper end of the movable receiving plates E E'.

A sheet to be folded is fed from the stationary receiving plate e' and passes between 50 a plurality of tapes or cords G G' which engage respectively the upper and lower surfaces of the sheet. These cords G G' pass over pulleys or disks g g' mounted on driven shafts g^2 g^2 suitably 55 journaled on the receiving end of the frame of the machine and over grooved ends of plates g^3 g^4 respectively at the other end of the folding mechanism. These plates also support those runs of the cords which engage 60 the article. The pulleys g g' and the ends of the plates g^3 g^4 are so arranged relatively to each other that the lower runs of the depressing cords G engage the upper 65 face of the sheet to be folded, and the upper runs of the supporting cords G' en-

gage the lower face of the sheets. The cords G G' are arranged at equal distances from each other, the distances between the cords at the receiving end of the folding device depending upon the width to which 70 it is desired to fold the article. In order to prevent wrinkling of the sheets, the distance or space between adjacent sheet-engaging cords is the same from their receiving to their discharge ends, this space being 75 in a substantially horizontal direction at the receiving ends of the cords and in a substantially upright direction at the discharge ends of the cords. The sheet engaging runs of the cords converge horizontally and diverge vertically in a direction away from the receiving end of the folding mechanism B, so that the run of the supporting cord engaging the lower face of 80 the sheet draws the portion of the sheet 85 which it engages upwardly, and the run of the depressing cord engaging the upper face of the sheet draws the part of the sheet which it engages downwardly. In this manner each of the sheet-engaging 90 runs of the cords forms a fold of the sheet and the folds are brought close together by the converging of the cords horizontally. The plates g^3 g^4 may be suitably supported 95 from the frame of the machine in any desired manner, the plates g^3 being supported from above and the plates g^4 from below, so that the passage of the sheet lengthwise of the plates will not be interfered with.

It is desirable to construct the machine in 100 such a manner that the cords of the folding mechanism may be adjusted toward and from each other, so that the width of the folds can be varied. Any suitable means 105 may be employed for this purpose. In the construction shown, the pulleys g g' are adjustably secured on the shafts g^2 by means of set screws h or the like, and the plates g^3 g^4 are secured on supporting straps or rods h', which are mounted on rods H 110 extending transversely of the frame of the machine and which straps h' are adjustable horizontally lengthwise of the rods and adapted to be secured in the desired positions by means of set screws h'. The ends 115 of the rods H are adjustable vertically on bars h' secured on the sides of the machine, so that the cords can be adjusted in any desired direction. h' represents idler 120 pulleys or wheels mounted on links h' which are pivoted on the plates g^3 g^4 and are yieldingly held by means of springs h' in positions to cause the pulleys h' to engage the cords and maintain the same taut. Any other means may be employed for this purpose. Guide pins h' are secured on the plates g^3 g^4 and guide the cords into proper 125 relation to the driving pulleys g g'.

The folds of the sheet are brought as closely together as is practicable by means 130

of the cords. In order to bring the folds still more closely together, the partially folded sheet, after leaving the cords, passes to a plurality of converging plates or blades 5 I I', one blade being provided for each of the cords and passing between the folds for supporting the sheet in its folded position as it is moved to the discharge end of the machine by the cords. The folds of the 10 sheet at the discharge ends of the blades I I' are in close proximity, being only separated by the blades, which are quite thin at their discharge ends. The blades I I' are supported from the frame of the machine 15 by any suitable means, such as rods i which are adjustably mounted in sleeves i' secured on brackets i'' , so that the blades can be adjusted vertically in accordance with the width of fold desired. The blades I' 20 which enter between the folds and engage the lower surface are supported from underneath and the other blades are supported from above.

The sheet after passing the blades I I' 25 passes between upright rolls K K', which serve to draw the sheets from the blades to discharge the same from the folding mechanism B. Since the folded sheet leaving the blades I I' is in a substantially upright position it is therefore desirable to turn the same through a right angle to deliver the sheet substantially horizontally from the folding mechanism. For this purpose, belts k k' pass around the rolls K K' and around 30 horizontal rolls k^2 k^3 , so that the belts passing around the rolls turn through substantially a right angle. The folded sheet passes between the belts and is turned by the belts through substantially a right angle, so that 35 the folded sheet is discharged from the folding mechanism in a horizontal position. In the construction shown, the horizontal rolls k^2 k^3 are arranged at the front side of the machine, so that the folded sheets are delivered to this side of the machine, but any other arrangement may be employed if desired.

Any other means for removing the sheets from the discharge ends of the blades I I' 40 may be employed.

The folding mechanism B is primarily intended for folding large sheets. In case the machine is used to operate on sheets of different sizes, for example, as would be the 45 case if the machine were used in connection with an ironing machine in a laundry, it might be desirable to provide another set of folding mechanisms on which smaller articles, such, for example, as towels, could be 50 folded. For this purpose, the folding mechanisms C C are provided which are substantially the same in construction and operation as the folding mechanism B except that 55 fewer cords are employed, three being used 60 in each mechanism in the construction 65 shown. L L' represent the cords of the folding mechanisms C, l the blades at the discharge ends of the cords, and l' the discharge belts of the mechanisms C. These belts, after taking the folded sheets from 70 the blades l, place them on a traveling belt or conveyer l^2 from which they are removed from the machine, the conveyer shown also delivering the folded sheets to the front side of the machine. In order to prevent 75 the folded sheets from being placed one on top of another on the belt or conveyer l^2 , the discharge belts l' are placed in staggered arrangement, Fig. 9, so that each belt l' places its folded sheets on a different part of the 80 conveyer l^2 .

Any suitable means may be employed for actuating the various movable parts of the machine. In the construction shown, power is applied to the machine from any suitable 85 source (not shown) through a pulley M mounted on the upper of the two shafts g^2 . The lower shaft g^2 is driven from the upper shaft by means of spur gears m m' . Corresponding shafts for driving the cords L L' 90 are driven from the upper shaft g^2 by means of a sprocket chain m^2 and gears m^3 m^4 . The upper shaft g^2 is connected by means of a sprocket chain m^5 with a sprocket wheel m^6 mounted on a shaft m^7 which is connected by means of bevel gears m^8 m^9 to a shaft m^9 on which the roll K of the discharge belts for the folded sheets is secured. This shaft is connected with the shaft of the other roll K' by means of gears m^{10} . A 100 similar drive mechanism is employed in connection with each of the discharge belts of the folding mechanism C, including a sprocket chain n and bevel gears n' .

When the machine is employed for folding sheets of uniform width, the cords are 105 adjusted so as to fold the sheet the desired number of times, and so that the folds are of uniform width. When, however, the machine is used for folding sheets of different widths, the sheets are preferably so fed to the folding machine that one edge of each sheet is in a definite relation to the folding mechanism, for example, so that the fold at this edge of the sheet will be of the same width as the other folds. In the construction shown, the edges of the sheets are placed 110 in a definite relation to the front side of the machine, shown at the left in Fig. 4. This may be accomplished by placing a mark 115 upon the ironing machine or other device with which the edge of the sheet may be aligned to cause the same to enter into the folding mechanism in proper relation to the one side thereof. The fold at the opposite side of the sheet in Fig. 4 will then be of greater or less width than the other folds, depending upon the width of the sheet. If 120 the sheet is of such width that the edge at the rear side of the machine will rest upon 125

- one of the supporting cords G' and will not extend beyond the depressing cord G , this edge of the sheet will be folded by the mechanism above described, without difficulty.
- 5 If, however, the edge of the sheet at the rear side of the machine extends beyond a depressing cord G and does not reach the next supporting cord G' , the unsupported edge portion of the sheet will be of greater width 10 than the other folds of the sheet, and means are preferably provided for supporting and folding this edge of the sheet in such a case, those shown in the drawings being constructed as follows:
- 15 Two belts $O O'$ are arranged between a depressing cord G and an elevating cord G' in such a manner that the edge of the sheet at the rear side of the machine, if the same extends beyond a depressing cord G , will pass between the belts. The belts pass around substantially horizontal rollers $o o'$ at the receiving end of the folding mechanism and around rods or brackets $o^2 o^3$, Figs. 6 and 7, at the other 20 end of the mechanism, the brackets being substantially upright so as to deliver the overlapping edge of the sheet between the belts $O O'$ at the discharge end of the mechanism in a substantially upright position.
- 25 The rollers $o o'$, Fig. 5, are mounted upon brackets $o^4 o^5$ loosely secured on the upper and lower shafts $g^2 g^2$ respectively, and the rollers $o o'$ are driven from the upper and lower shafts $g^2 g^2$ respectively, by means 30 of belts o^6 or other suitable means. In the construction shown, the lower roller o' is supported by means of a bracket o^7 secured on the frame of the machine and the upper roller rests by gravity upon the lower roller.
- 35 In order to feed the rear edge of the sheet between the belts $O O'$, the receiving plate e' is provided with an extension o^8 which supports the edge of the sheet until it passes between the belts. Any other suitable means 40 for folding the unsupported edge of the machine may be employed.
- The sheets after being folded longitudinally by means of the mechanism described, can be removed from the machine 45 and folded in the other direction by hand, or if desired, a folding mechanism may be employed for folding the sheets in a transverse direction. In the mechanism shown for this purpose a plurality of plates p are 50 linked or hinged together to form an endless chain P . This chain passes around sprocket wheels R by means of which movement is imparted thereto and the movement of the chain and of the individual plates p 55 relatively to each other is preferably controlled by means of cam tracks $S S'$ and studs or pivots extending beyond the sides of the chain. In the construction shown, long and short pivots or studs $p' p^2$ are 60 arranged alternately throughout the length 65 of the chain and may, if desired, be formed as in the construction shown by the extending ends of the hinge pintles connecting the plates p . The ends of the studs are preferably provided with anti-friction rollers 70 p^3 adapted to engage in the cam tracks $S S'$. The sprocket wheels R have recesses r into which the studs $p' p^2$ enter, and the rotation of the sprocket wheels in a clockwise direction in Fig. 10, causes the studs 75 to enter the recesses r and thus imparts motion to the chain. The two cam tracks S are arranged so that they terminate in such relation to the sprocket wheels and to the chain that the ends of the long studs p' engage with these tracks, while the shorter studs continue to move with the sprocket wheels until they come into engagement with the tracks S' . The two tracks diverge 80 in such a manner that the plates constituting the chain swing about their pivots or hinges so that each plate forms an acute angle with the adjacent plate. The movement of the sprocket wheel causes the plates in this position to move along the horizontal parts of the tracks $S S'$ and then to move downwardly into the upright portion of the tracks. The chain P and its coöperating parts are so arranged relatively to the discharge belts $k k'$ that the sheet which has 85 been folded longitudinally is discharged lengthwise over a plate or table r' and onto the plates constituting the chain. As these plates assume angular relations to each other, the sheet supported thereon is folded 90 as indicated in dotted lines in Fig. 13, and when the plates reach the upright part of the tracks $S S'$ at the discharge end of the machine, the folded sheets may be removed 95 from the machine by pulling them out of engagement with the plates, recesses or notches p^4 being provided in the plates to facilitate the removal of the folded sheets. After the folded sheets have been removed from the plates, the plates are drawn by the sprocket 100 wheels along lower horizontal guide tracks s and again pass around the sprocket wheels.
- By means of the machine described, the sheets pass continuously through the machine and since no reciprocating parts are 105 employed, the machine can be operated at a high rate of speed. The machine described is so constructed that it can be placed into operative relation to an ironing machine in a laundry and the sheets as they issue 110 from the ironing machine, pass directly to the folding machine without requiring any manual labor. A large amount of labor is saved by the folding machine, which requires practically no attention, except by 115 the operator who removes the folded sheets from the machine. The machine is also capable of operating on small as well as on large sheets, and the changing from one 120 size of sheets to another is a simple opera- 125
- 130

tion and can be made in an instant. The machine is inexpensive to construct, simple in its operation and comprises no parts which will easily wear out.

5. I claim as my invention:

1. In a sheet folding machine, the combination of a plurality of cords arranged to alternately engage opposite faces of a sheet for folding the same as the sheet passes through the machine, said cords converging horizontally and diverging vertically from the receiving end of the machine to divide the sheet into folds and to bring the folds together, means for adjusting the receiving ends of said cords horizontally toward and from each other, means for adjusting the discharge ends of said cords vertically toward and from each other, a plurality of substantially upright blades arranged at the discharge ends of said cords and converging from the receiving end of the machine, and means for adjusting said blades vertically with regard to each other.
2. In a sheet folding machine, the combination of a plurality of cords which are adapted to receive a sheet and which converge horizontally from the receiving end of the machine to fold the sheet when the same passes through the machine, means for adjusting said cords relatively to each other to adapt the machine to vary the size of the folds, a plurality of substantially upright blades arranged at the discharge ends of said cords and converging from the receiving end of the machine, and means for adjusting said blades vertically.
3. In a sheet folding machine, the combination of a plurality of endless movable cords which are adapted to receive a sheet and which converge horizontally for folding the sheet, a plurality of converging blades arranged at the discharge ends of said cords and adapted to receive the sheet from the cords for bringing the folds of the sheet together, and a pair of contacting belts between which the folded sheet enters upon leaving the blades and which withdraw the sheet from the blades, said belts passing over pulleys arranged in a plane extending substantially at right angles to the planes of said blades for turning the sheet through a substantially right angle.
4. In a sheet folding machine, the combination of a plurality of folding mechanisms arranged one above the other, and guide plates arranged side by side and pivotally mounted at one end and adapted to receive the sheets to be folded at said end, said guide plates being adjustable about their pivots independently of each other to direct sheets to be folded to any of said folding mechanisms.
5. In a sheet folding machine, means which engage a sheet at intervals for alternately supporting and depressing adjacent portions of the sheet and which converge to bring the portions of the sheet toward each other to effect the folding of the same and to move the sheet through the machine, and a pair of contacting belts arranged substantially parallel to said cords adjacent to one edge of the sheets, the contacting faces of the belts moving in the same direction and being so arranged that an unsupported edge portion of a sheet enters between the same, said belts being twisted to fold said edge portion into proximity to the other folds of the sheet.
6. In a sheet folding machine, means which engage a sheet at intervals for alternately supporting and depressing adjacent portions of the sheet and which converge to bring the portions of the sheet toward each other to effect the folding of the same and to move the sheet through the machine, said means being movable and carrying the sheet through the machine while folding the same, and a pair of contacting belts so arranged relatively to said means as to engage the edge portions of sheets, the contacting faces of said belts moving in the same direction and at the same speed as said supporting means and being so arranged that the unsupported edge portion of a sheet enters between the same, said belts being twisted to fold the edge portion of the sheet into proximity to the other folds of the sheet.
7. In a sheet folding mechanism, the combination of a plurality of endless cords, pulleys for actuating said cords, some of said cords having runs engaging the lower face of the sheet for supporting the same and some of said cords having runs engaging the upper face of the sheet for depressing the same, said sheet-engaging runs of the cords extending in directions to bring the folds of the sheet together, and a pair of contacting belts arranged at one edge of the mechanism between a supporting and depressing cord, the contacting faces of said belts moving in the same direction and at the same speed as said cords, said belts being so arranged that a portion of a sheet enters between the belts, said belts being twisted to fold the portion of the sheet twisted thereby into substantially the same angular position as said sheet would have been folded by said supporting and depressing cords.
8. In a sheet folding machine, the combination of a plurality of endless cords, pulleys for actuating said cords, some of said cords having runs engaging the lower face of the sheet for supporting the same and some of said cords having runs engaging the upper face of the sheet for depressing the same, said sheet-engaging runs of the cords extending in directions to bring the folds of the sheet together, and a pair of contacting belts adapted to receive an

- edge portion of a sheet and arranged at one edge of the machine adjacent to a depressing cord, said belts being twisted to fold the edge of the sheet upwardly.
- 5 9. In a sheet folding machine, the combination of a plurality of endless cords having runs adapted to engage the sheets for folding the sheets lengthwise, co-operating belts arranged in operative relation to said cords and twisted through substantially a right angle, and transverse folding mechanism to which said sheets are delivered by said belts.
- 10 10. In a sheet folding machine, the combination of mechanism for folding a sheet lengthwise, transverse folding mechanism comprising a plurality of pivotally connected plates which are adapted to be placed substantially into alinement with each other to receive said folded sheet, and means for swinging the plates into an acute angular relation to each other to effect the folding of the sheet.
- 15 11. In a sheet folding machine, the combination of mechanism for folding a sheet lengthwise, transverse folding mechanism to which the sheet is delivered from said first mentioned mechanism and which comprises a plurality of pivotally connected plates upon which said folded sheet is placed, and means for swinging said plates into an acute angular relation to each other for effecting the folding of the sheet.
- 20 12. In a sheet folding machine, the combination of mechanism for folding a sheet in one direction, and secondary folding mechanism which comprises a plurality of pivotally connected plates forming an endless chain upon which said folded sheet is laid, means for imparting movement to said chain, and means for swinging the plates of said chain into acute angular relation to each other for effecting the folding of the sheet.
- 25 13. In a sheet folding machine, the combination of mechanism for folding a sheet in one direction, and secondary folding mechanism which comprises a plurality of pivotally connected plates forming an endless chain upon which said folded sheet is laid, means for imparting movement to said chain, means for guiding the movement of said plates and which engage the plates and cause each plate to move out of alinement with the other plates and into an acute angular relation to adjacent plates for effecting the folding of the sheet.
- 30 14. In a sheet folding machine, the combination of mechanism for folding a sheet in one direction, and secondary folding mechanism which comprises a plurality of pivotally connected plates forming an endless chain upon which said folded sheet is laid, means for imparting movement to said chain, studs projecting from said plates, and a cam track adapted to be engaged by said studs and causing each plate to swing into acute angular relation with adjacent plates to offset the folding of the sheet.
- 35 15. In a sheet folding machine, the combination of mechanism for folding a sheet in one direction, and secondary folding mechanism which comprises a plurality of pivotally connected plates forming an endless chain upon which said folded sheet is laid, means for imparting movement to said chain, short and long studs projecting alternately from the pivotal axes of the plates, cam tracks arranged to be engaged by said short studs, and cam tracks engaged by said long studs, said two sets of cam tracks diverging to cause each plate to move out of alinement with the other plates and into acute angular relations with adjacent plates to effect a folding of the sheet.
